UNITED STATES PATENT OFFICE.

EDWARD ERICKSON, OF BEVERLY, MASSACHUSETTS, ASSIGNOR TO UNITED SHOE MACHINEY CORPORATION, OF PATERSON, NEW JERSEY, A CORPORATION OF NEW JERSEY.

MACHINE FOR OPERATING ON SHOE BOTTOMS.

Application filed November 1, 1919. Serial No. 335,030.

To all whom it may concern:

Be it known that I, EDWARD ERICKSON, a citizen of the United States, residing at Beverly, in the county of Essex and State of

5 Massachusetts, have invented certain new and useful Improvements in Machines for Operating on Shoe Bottoms; and I do hereby declare the following to be a full, clear, and exact description of the invention, such 10 as will enable others skilled in the art to which it appertains to make and use the same.

This invention relates to machines for operating upon boots and shoes and, in the 15 illustrated embodiment herein disclosed, is shown as applied to a machine for preparing welted, unsoled shoes for the reception of the outsole. Machines of this type are known as welt butting and tacking machines, an example being shown in United 20 States Letters Patent No. 1,373,553, granted April 5, 1921, on my application. It is to be understood, however, that the several features of the present invention are not 25 limited in their application to machines of this type.

One of the objects of the invention is to provide a machine of the above indicated 30 character with simple and effective means for removing the waste ends of the welt that are severed during the butting or scarfing operation and for preventing an accumulation of wax and threads upon the cutters.

35 Accordingly, one of the features of the invention resides in the provision of waste-end removing implements disposed directly above and in sliding engagement with the respective welt-butting cutters and which 40 are mounted upon the cutter carriers and are laterally actuated across the cutters to discharge the waste ends and to scrape off the wax and threads therefrom after each butting or scarfing operation. Moreover, the 45 mechanisms for effecting the actuation of the waste-removing implements are mounted upon and are movable with the cutter carriers and are also disposed on the outer sides thereof where space is unrestricted.

50 Another object of the invention is to provide a machine of this general class with means for lasting in the uppers under predetermined pressure prior to the tacking

opération and to effect this result automatically so as to relieve the operator of the care 55 and effort heretofore required for this purpose.

Therefore, another feature of the invention contemplates the provision of power-operated means for automatically forcing 60 the welt supports or crease finders inwardly under predetermined pressure which pressure may be applied subsequent to the welt-butting operation, whereby the uppers are lasted in independently of the operator just 65 prior to the tacking operation. As shown herein the power-operated means acts through a spring, by compression of which the required pressure is applied to the welt supports. 70

Another object of the invention is to provide adequate means for causing the welt-butting cutters to bevel off the ends of the welt, not only longitudinally thereof but also transversely outward with respect thereto, 75 in such manner that the stitches remain intact throughout substantially the full length of the scarfs, while the ends of the welt are cut off squarely.

To this end, a feature of the invention lies 80 in the provision of welt supports or crease finders that may be adjusted to any desired longitudinal angularity to the plane of the cutters whereby the requisite longitudinal bevels are produced, and moreover, that are 85 so transversely inclined and concaved as to receive and support the inner portions of the welt adjacent the stitches in such position that the welt-butting cutters bevel off the welt ends to thin edges transversely outward without cutting the stitches at the inner edges of the welt. Furthermore, shear plates or shoulders are provided at the rear 90 extremities of the crease finders which co-operate with the cutters to ensure that the 95 welt is cut off squarely.

Other objects of the invention and features by which they are attained will become apparent to those skilled in the art from the following description of the preferred embodiment of the invention illustrated in the accompanying drawings, in which:—

Figure 1 is a view in elevation of the left-hand side of a machine constructed in accordance with the invention, certain por-

tions of the frame being broken away to disclose certain parts of the operating mechanism; Fig. 2 is a sectional plan view on the line 2—2 of Fig. 1, showing the swinging side frames, the operating mechanism for the welt-butting cutters, and the mechanism for removing the severed waste ends of the welt; Fig. 3 is a sectional plan view showing one of the waste end removing mechanisms in an intermediate position during its operation; Fig. 4 is a view in side elevation of the right-hand side frame with its welt-butting and tacking mechanism, certain parts being broken away from the inside face of the side frame for the sake of clearness; Fig. 5 is a detailed view in vertical section of the lower end of one of the tacker mechanisms; Figs. 6, 7 and 8 are detailed views in side elevation, illustrating different positions of a welt-butting cutter and tacker mechanism at different times during the welt-butting and tacking operations, these views being similar to that of Fig. 4; Figs. 9 and 10 are views, partially in section and partially in side elevation, of a portion of the mechanism for effecting the automatic lasting in of the upper subsequent to the welt-butting operation, said views respectively illustrating the mechanism at different stages of its operation; Fig. 11 is a view in side elevation, showing the relative positions of the crease finder, heel-seat guard, presser foot, and welt-butting cutter in the process of scarfing off the end of a welt; Figs. 12, 13 and 14 are respectively a side elevation and two sectional views of one of the crease finders; Fig. 15 is a perspective view of the end of a welt after the butting operation has been performed upon it; Figs. 16 and 17 are respectively detailed sectional views taken on the lines 16—16 of Fig. 2 and 17—17 of Fig. 3 and showing the construction and arrangement of a portion of one of the mechanisms for actuating the one of the waste end removing implements; Fig. 18 is an exploded perspective view of the adjustable welt support or crease finder carried by the right-hand side frame; Fig. 19 is a view in perspective of a portion of one of the tacker mechanisms, illustrating particularly the adjustable section of the tack delivering tube in cooperative registering relation with the inclined tackway passage at the lower end of the tacker bar slide for introducing the tacks to the tacker nozzle; and Fig. 20 is a perspective view of one of the welt-butting cutters.

In the preferred embodiment of the invention illustrated in the drawings, and with particular reference to Fig. 1, the machine is provided in general with mechanism for supporting the shoe in operative position and the rear ends of the welt in position for the butting operation, mechanism for butting both of the welt ends simul-

taneously, and mechanism for thereafter inserting tacks to secure the lasted in upper to the insole. These various devices are mounted upon a head supported upon a column 24, the head having a forwardly projecting goose neck 26 at the front of which are journaled vertical pivot rods 28 and 30 (Figs. 2 and 4) on which are supported a pair of swinging side frames 32 and 34. The side frames, as will be more fully described later, support the welt-butting and tacking mechanisms, while a bracket 38 is bolted to a table 40 cast on the upper side of the goose neck 26 and carries a tack separating and delivering mechanism 42. Any suitable tack separating mechanism may be employed, although the preferred form is that shown and described in the patent hereinbefore referred to.

The moving parts are driven by the rotation of a driving shaft 44 which is disposed at the rear of the machine and extends transversely of the head thereof, and which is enveloped by means of a guard plate 46. The driving shaft 44 is normally at rest but may be connected at the will of the operator by means of a single revolution clutch of any well-known form (not shown) to a power shaft 48 which is continuously driven by a belt cooperating with a pulley 50.

As is usual in machines of this character, the shoe is supported and positioned vertically for the welt-butting and tacking operations by means of thin plates 52 usually termed welt supports or crease finders (Figs. 2, 4, 11 and 18), that are carried at the forward ends of each of the swinging side frames 32 and 34 and which are inserted in the welt crease at each side of the shoe substantially at the rear end of the inseam. It will be understood that, as is common practice in this type of machine, the crease finders are forced into the welt crease by the inward movement of the swinging side frames 32 and 34 about their pivot rods 28 and 30, the crease finders performing the function of supporting the shoe during the welt-butting and tacking operations. In addition to their usual function and by reason of further inward movements imparted thereto independent of the operative after the welt-butting operation, they also serve to automatically last in the upper just prior to the actuation of the tacking mechanism.

In order to position the shoe for the proper engagement of the crease finders 52 with the welt crease, the machine is provided with a back gage 54 (Figs. 1 and 2) which may be adjusted longitudinally so as to properly locate the heels of shoes of different sizes for the inward movement of the crease finders. The back gage may be suitably adjusted in position by means of a locking handle 56. The back gage 54 and its adjustable locking handle 56 form no part of the present in-

vention, except as they perform necessary functions in definitely locating the shoe while being operated upon, and since the specific structural details and mode of operation thereof are fully set forth in the above mentioned patent, no description thereof is deemed necessary.

The forward ends of the swinging side frames 32 and 34 are normally held apart by means of a spring 58, (Fig. 2) the ends of which are attached to the rear ends of the respective side frames. In order that the side frames may move together, they are provided with intermeshing toothed segments 60 and 62, respectively, through which the lower ends of the pivot rods 28 and 30 extend. A treadle mechanism is provided to overcome the force of the spring 58, and bring together the crease finders 52 carried by the forward ends of the side frames into position to support a shoe and the ends of the welt for the operations to be performed thereon. This mechanism comprises a treadle 64 (Fig. 1) which is pivoted at 66 in the lower part of the column 24 and is connected by a treadle rod 68 to a horizontal arm 70 of a bell crank lever that is pinned to a transverse rock shaft 72 journaled in the lower part of the machine head. Referring particularly to Fig. 9, this bell crank lever is provided with a vertical arm 74 having a socket which receives one end of a coiled spring 76, the other end of which is seated in a socket formed in an arm 78 which projects upwardly and has two legs which straddle the bell crank lever 70-74, by means of which it is loosely pivoted upon the rock shaft 72. The upper end of the arm 78 is provided with a horizontal head 80 in each end of which there is formed a socket for the reception of the inner ends of a pair of inclined struts 82 which extend between said head and the socketed rear ends 84 of the respective swinging side frames 32 and 34.

The treadle 64 is normally held in raised position by a spring 86 connecting it to the column 24 whereby the coiled spring 76 is normally uncompressed, as shown in Fig. 9. When the treadle 64 is depressed, however, the lowering of the treadle rod 68 operates through the bell crank lever 70-74 and the spring 76 to move the vertical arm 78 to the left which operates upon the inner ends of the two struts 82 so as to bring the struts into position approaching alinement. Consequently the rear ends of the side frames 32 and 34 are forced apart in opposition to the action of the spring 58. This outward movement of the rear ends of the side frames causes a corresponding inward movement of their front ends and therefore brings the crease finders 52 into the welt crease of the shoe which has previously been placed with its heel end against the back gage 54 and

which is held by the operative at a proper height.

If the forward ends of the side frames 32 and 34 were always allowed to be opened to their fullest extent by the spring 58, a considerable inward movement would be required to cause the crease finders 52 to properly engage and support shoes of narrow widths. In order to obviate the necessity of such an extensive movement, an adjustable stop is provided for limiting the outward movement of the forward ends of the side frames, which may be adjusted so as to provide an opening movement commensurate with the width of the shoe to be operated upon. This stop is best shown in Fig. 2 and comprises a screw 88 threaded into the rear portion of the side frame 34 and provided with a head 90 adapted to engage a wear plate 92 carried by a portion of the segment 60 on the side frame 32. The head 90 may be adjusted toward and from the plate 92 by means of a hand wheel 94 that is disposed at the outer end of the screw 88. The distance of the head 90 from the wear plate 92 obviously determines the amount which the forward ends of the side frames can open under the influence of the spring 58.

It will be observed that on pressing the treadle 64, only so much pressure can be placed upon the welt crease by the crease finders as is permitted by the strength of the spring 76, for as soon as the pressure equals the strength of the spring, said spring will begin to yield without further movement of the arm 78 or further straightening of the toggle formed by the struts 82. The effectiveness of the spring 76 may be varied by the adjustment of a threaded block 96 to suit the strength of the material which is being operated upon, the proper adjustment being relatively light and such as to merely support and hold the shoe during the welt-butting operation but not such as to subject the shoe to a pressure sufficient to last in the upper to its final position. Continued depression of the treadle will, however, continue to rotate the rock shaft 72, which movement is utilized through suitable mechanism (not shown) to operate the single revolution clutch, hereinbefore referred to, in order to effect an operative driving connection between the power shaft 48 and the driving shaft 44, whereby the mechanisms for operating the various moving parts of the machine are set into motion. No description of the means for performing this function is deemed necessary inasmuch as it pertains only indirectly to the present invention. A full description of the preferred form of means for accomplishing this result may be found in the above-mentioned patent to which reference may be had if desired.

In order to render it unnecessary for the operative to hold his foot on the treadle 64 after the driving shaft 44 and the various operating mechanisms actuated thereby have been set into motion and during the continuance of their operations, automatic means is provided for locking the swinging side frames 32 and 34 in the positions to which they have been moved by the depression of the treadle. This locking means is illustrated particularly in Fig. 1 and comprises a vertical arm 98 that is secured to the left-hand end of the rock shaft 72 and which is pivotally connected at its upper end to the forward end of a rectangular rod 100. The rear end of the rod 100 extends through a rectangular opening in an arm 102 depending from and pivoted freely on a horizontal stud 104 carried by the machine frame. The lower end of the arm 102 is normally pulled forward by a spring 106 connected between the arm and the frame. When the machine is in a position of rest, a pin 108 projecting outwardly from the periphery of a disk 110 that is secured to the left-hand end of the driving shaft 44 is in engagement with an upwardly projecting ear 112 which forms an extension of the arm 102. Thus, the arm 102 is maintained in such position that the rectangular rod 100 is capable of sliding freely through the rectangular opening in said arm. As soon, however, as the driving shaft 44 has been connected to the power shaft and said driving shaft begins to rotate, the pin 108 is removed from its engagement with the ear 112 thus permitting the spring 106 to rock the arm 102 to an angular position with relation to the rod 100, whereby the corners of the opening in the arm above and below the rod are caused to bite and bind on the rod and act as a lock to prevent the rock shaft 72 from being rotated to initial position by the extended treadle spring 86.

The swinging side frames remain locked in their inner shoe-supporting positions during the cycle of operation of the several mechanisms which operate upon the shoe and until just subsequent to the time when the single revolution clutch is thrown out to disconnect the driving shaft 44 from the power shaft 48, at which time the pin 108 on the periphery of the disk 110 is again brought into cooperative engagement with the extension 112 of the pivotally mounted locking arm 102. This locking arm is thereby returned to its initial position normal to the rod 100 so as to release said rod and the rock shaft 72, whereupon the spring 58 which connects the rear ends of the side frames 32 and 34, operates to swing the frames outwardly about their pivot rods 28 and 30 and thus release the shoe from its engagement with the supporting crease finders 52. The treadle spring 86 also

functions to restore the treadle 64 and mechanism associated therewith to their initial inoperative positions.

Having positioned and supported a shoe between the side frames, and the driving shaft 44 having been connected to the power shaft in the general manner hereinbefore described, the respective ends of the welt are beveled or scarfed by the welt-butting mechanism, after which the crease finders 75 are forced inwardly to last in the upper which, together with the ends of the welt if desired, are thereupon secured to the insole by the tacking mechanism.

Referring particularly to Figures 1, 2 and 4, the welt-butting mechanism will now be described. The actuation of this mechanism is effected through a connecting rod 116, one end of which is associated with a crank 118 forming a part of the driving shaft 44 and the other end of which is connected to a piston 120 which is guided within a cylindrical way 122 cast centrally in the lower part of the goose neck 26. Projecting from the forward end of the piston 120 is a connecting rod 124, which is provided with an H-shaped head 126 (Fig. 2) which lies horizontally with the legs of the H pointing outwardly toward the side frames 32 and 34. The slots 128 and 130 formed between the legs of the H carry slide blocks 132 and 134 which are drilled vertically for the reception of vertical pins 136 that are carried in ears 138 that project inwardly from the welt-butting cutter operating slides 140 and 142. With this construction, a rotation of the crank 118 to withdraw the piston 120 within its guide-way 122 causes the slides 140 and 142 to be actuated in a rearward direction to effect the operation of the welt-butting and tacking mechanisms. The slides 140 and 142 are mounted for sliding movement in the respective side frames 32 and 34, which, in their supporting positions, are usually at an angle to the line of movement of the piston 120. Irrespective of this angularity, the slide block connections just described between the slides and the H-shaped head 126 of the connecting rod 124, insure proper operation, inasmuch as the slots 128 and 130 in the H-shaped head provide for outward movements of the sliding blocks 132 and 134 as the slides are actuated.

Since the mechanism carried by each of the side frames is like the other except that it is reversely disposed, it will be sufficient to describe the mechanism at one side only, and the mechanism upon the right-hand side frame 34 will be used to disclose the construction now to be described. Referring particularly to Figs. 2 and 4, which illustrate the various mechanisms on the side frame 34 in positions of rest, the welt-butting cutter slide 142 rests upon a way 146

formed at the lower end of the side frame. The slide is T-shaped in cross section and is guided during its rearward movement by the side walls of the side frame which are 5 suitably recessed to receive its T-head. The upper part of the slide 142 is channel shaped for a greater portion of its length and its side walls are cut and drilled at two separate points for the reception of the lower 10 cylindrical ends of two links 148 and 150. The upper ends of these links are received in similar openings formed in a channel shaped welt-butting cutter carrier 152, but the link openings in the carrier are further 15 apart than those in the slide, as shown best in Fig. 4. This mounting of the cutter carrier 152 permits it to be rocked back and forth relative to the cutter slide 142 to lower and raise the welt-butting cutter 154 relative 20 to the shoe. The movement in a rearward direction is limited by the end of the carrier 152 abutting against a shoulder 155 formed on the slide and the movement in a forward direction is limited by the engagement 25 of an adjustable stop screw 156 with the surface of the nose 158 of the slide.

The welt-butting cutter 154 has a uniform triangular cross section throughout its entire length, as shown in Fig. 20, and is supported 30 in a V-shaped transverse groove in the forward end of the cutter carrier 152 by means of a clamping member 160 which engages the rear surface of the cutter and which is bolted to the forward end of the cutter in 35 clamping relation thereto. The angularity of the V-shaped groove corresponds to that of the planes which define the cutting edge of the cutter and by reason of the clamping action of the member 160, the cutter is 40 forced into intimate and firm engagement with the cooperating sides of the groove, whereby the cutter is firmly held in position. In order to protect the cutting edge, a recess 45 161 is provided at the apex of the groove so that it is impossible for the edge to be brought into contact with the carrier. The elongated uniform configuration of the cutter is of particular importance since the cutter may be utilized in either the right or the left cutter carrier, it being understood 50 that one end of the knife is clamped in the receiving groove while the other end projects inwardly from the cutter carrier into position for operation upon the welt ends. Obviously if the knife in the right hand carrier becomes dull, or worn, it may be removed and placed in the left hand carrier, and vice-versa.

In order to smooth out and hold down 55 the welt in advance of the cutter and to pull any tacks which may accidentally be left in the shoe in the path of the cutter, a presser foot 162 is positioned just ahead of the cutter and projects laterally from a substantially vertical shank 164 that is slidably

mounted in a guideway in the end of the cutter carrier 152. The shank 164 is provided with a lateral pin 166 which engages the lower end of a coiled spring 168 that is contained in a recess adjacent said guideway and the upper end of which abuts against an adjustable threaded block 170 by means of which the compression of the spring may be varied as desired. By this construction the presser foot 162 is yieldingly urged into engagement with the work. As shown best in Fig. 2, the presser foot 162 is provided with a beveled and toothed forward edge by which it may engage beneath the heads of and pull any tacks which may have inadvertently been left in the shoe in the path of the welt-butting cutter.

The crease finders 52, hereinbefore referred to, serve not only to engage the welt crease and position the shoe during the operations upon it, but also support and hold the ends of the welt in such positions that they are beveled off both longitudinally and transversely outward, and moreover, are so shaped that the inseam stitches are not cut 80 during the butting operation and the ends of the welt are squarely cut off.

The crease finders 52 are adjustably supported, to accommodate varying styles of 85 shoes, at the forward ends of the swinging side frames 32 and 34 just below the nose 158 of the welt-butting cutter slides 140 and 142. The form and mounting of these 90 crease finders may be best understood by reference to Figs. 11, 12, 13, 14 and 18 which 95 illustrate the crease finder 52 for the right-hand side frame 34. The crease finder is provided with a curved dove-tailed projection 174 which fits into a curved dove-tailed guideway 176 formed in the inner face of a 100 holder 178. The holder 178 is provided with a horizontal pin 180 which is received in a bore made for its reception in an adjustable block 182, which in turn has a horizontal pin 184 that projects into a bore 186 105 extending longitudinally into the front end of the side frame 34. The block 182 and consequently the crease finder 52 may be adjusted longitudinally of the shoe by turning a collared adjusting screw 188 threaded into 110 the frame 34 at 189 and engaging between the collar and head a slot in an ear 190 depending from the block 182. After having been adjusted, the pin 184 is held from movement by a locking pin 192. The crease 115 finder 52 may be adjusted transversely of the shoe if desired by loosening a locking pin 194 which binds on the pin 180 and then moving the holder 178 across its supporting shelf 196. Formed integrally with the 120 holder 178 is a guard plate 198 which extends over the heel seat of the shoe, as best shown in Figure 2, and over which the welt-butting cutter 154 travels after the welt has been severed.

For the purpose of producing a bevel or scarf having the characteristics hereinbefore enumerated, the crease finder 52 is provided with a peculiarly shaped and inclined upper surface 200. This surface is inclined transversely downwardly from its upper outer edge toward its inner edge which is curvilinear in form with the maximum curvature at the end of the crease finder adjacent the guard plate 198, as shown in Figure 11, at which point the outwardly inclined surface rises with considerable abruptness to meet the adjacent edge 206 of the guard plate 198, which edge forms a shoulder or shear plate with which the knife 154 cooperates to produce a squarely cut end on the welt. The inclination and configuration of the upper face of the crease finder is such that when the crease finder is positioned beneath the end of the welt, and the presser foot 162 irons and holds down the welt in engagement with the crease finder, said welt is so positioned that the welt-butting cutter 154, though it travels in a horizontal plane, scarfs off the end of the welt upon a bevel which, with respect to the normal plane of the welt, is inclined both longitudinally and transversely outward in such manner as to leave the inseam stitches intact and also to cut off the end of the welt squarely, as illustrated particularly in Figures 11 and 15. This will be clear from Figs. 13 and 14 which are transverse sections of the right hand welt support and crease finder on the lines 13—13 and 14—14 of Figure 12 respectively. It will be noted that the outer edge of the welt is held higher than the inner edge, the upper surface of the support being transversely inclined downwardly and inwardly with respect to the shoe. In Figure 14 the dotted line represents the plane of the cutting edge of the knife when it is about to begin its cut. The cut begins on the outer margin of the welt (Figure 15) and gradually progresses inwardly until it extends entirely across the portion of the welt which lies outside the stitches (Figure 13). The knife has now reached a point above maximum longitudinal curvature of the welt support which is greatest on the inner edge of the welt support and shades out to little or nothing at the outer edge. The welt is forced into this concavity of the welt support by the presser 162, and the knife, in finishing its cut, co-operates with the edge 206, which is parallel to the knife edge, to form a square end on the welt as shown in Figure 15. Obviously the length of the longitudinal bevel produced by the welt-butting cutter is determined by the longitudinal angularity or inclination of the upper surface of the crease finder 52 with respect to the path of travel of the cutter, and this inclination may be altered to obtain any length of bevel de-

sired by loosening the set screw 208 (Fig. 18) and shifting the crease finder angularly in its guideway 176, it being understood that the sides of this guideway are formed on arcs of circles having the joint between the crease finder and the guard plate 198 as the centre.

Since the movement of the welt-butting cutter slides 140 and 142 also actuates the tacker mechanisms, a description of the operation of the welt-butting mechanism will be deferred until the tacker mechanisms have been described. For an understanding of the tacker mechanisms, reference may be had particularly to Figs. 4 and 5 which illustrate the tacker mechanism associated with the right-hand swinging side frame 34, which mechanism is identical with that carried by the left-hand side frame 32. The tacker mechanism comprises a driver bar slide 212 which is seated for vertical sliding movement in a vertical rectangular groove or way in the forward edge of the side frame, which way is closed by a face plate 214. This slide 212 is bored longitudinally for the greater part of its length for the reception of a cylindrical driver bar 216. At its lower end the slide 212 is provided with a reduced bore through which a tack driver 218 extends (Fig. 5). The tack driver is secured to the lower end of the driver bar 216 by a nipple 220 in the usual manner. Also the lower end of the driver bar slide 212 has secured thereto by a nipple 222 a suitable tack nozzle 224. At its upper end the driver bar is provided with a head 226, the rear end of which is slotted and receives a vertically disposed track 228. A roll 230 is carried by the head 226 which engages the track 228 and guides the bar in its movement through the driver slide. The extreme upper end of the driver bar carries a conical cap 232 which is engaged by a socket on one end of a coiled driving spring 234. The other end of the driving spring is connected to a block 236 having a pin secured in a bearing 238 at the rear side of the driver bar slide 212.

Pivoted by its lower end at 240 in a vertical slot formed for its reception at the upper end of the face plate 214 is a latch lever 242 carrying at its upper end a roll 244 which is normally held in the path of movement of the driver bar head 226 by means of a spring pressed pin 246. The inward movement of the lever 242 is limited by an ear on the lever engaging a stop pin 248 mounted in the face plate 214. The driver head 226 is provided with a beveled surface 250 so located that on the upward movement of the driver bar 216 the roll 244 is forced to one side until the head has reached a position above the roll when said roll snaps back beneath the head and supports the driver bar against downward movement. The lever 242 is also provided with a boss

252 which projects into the path of and is adapted to be engaged by a cam 254 formed at the upper end of the driver bar slide 212 when said slide descends. The purpose of this action will presently be described. The driver bar slide 212 is provided at its rear side with teeth 256 which form in effect a rack which is engaged by the teeth of a segment 258 carried by a shaft 260 journaled in the side frame. The segment is provided with a downwardly projecting portion which forms a crank arm which is connected at its lower end by a link 262 to an arm 264 extending upwardly from and integral with the welt-butting cutter carrier 152. The link 262 embodies a turn buckle construction 266 intermediate its ends for the purpose of varying its length and therefore determining the lowermost position of the tack nozzle 224.

For the purpose of providing a frictional restraint or resistance to the movements of the driver bar slide 212, as will be herein-after more fully set forth, a friction plug 270 is seated in a recess in the face plate 214 and is urged by means of an adjustable coiled spring 272 against the forward side of the driver bar slide 212.

As best shown in Figs. 1 and 2, all of the moving parts just described, are carried by the swinging side frame 34, and are enclosed by means of a cover plate 274 which is suitably bolted to the outside thereof, while a similar cover plate 276 is provided for the side frame 32.

Having described the construction of the welt-butting mechanism and tacker mechanism, the operation thereof will now be set forth with particular reference to Figs. 4, 6, 7 and 8. Assuming the component parts of these mechanisms to occupy the positions shown in Fig. 4, in which positions the parts are at rest, and assuming that the power shaft 48 has been connected to the driving shaft 44, the operation of these mechanisms is as follows: When the driving shaft 44 begins to rotate, the piston 120 and its H-shaped connecting rod head 126 are drawn backwardly or away from the operative, which causes the welt-butting cutter slides 140 and 142 to be drawn rearwardly. Describing now the operation of the right-hand cutter only, as the slide 142 is retracted on its track 146, the resistance offered by the tacker mechanism and friction plug 270 causes the links 148 and 150 to pivot about their lower ends and tilt the welt-butting cutter carrier 152 forward until its stop screw 156 engages the nose 158 of the slide 142, as shown in Fig. 6. This brings the presser foot 162 into engagement with the upper surface of the welt supported upon the crease finder 52 and places the cutter 154 in the plane of the surface of the guard plate 198, this position being determined by proper adjustment of the stop screw 156. Further rearward movement of the piston 120 draws both the slide 142 and the carrier 152 rearwardly, causing the cutter to cut through and butt or bevel off the end of the welt, as shown in Fig. 11, the presser foot 162 during this movement serving to iron and hold down the welt upon the upper inclined and concaved surface of the crease finder 52. As the welt-butting cutter carrier 152 moves rearwardly, it draws with it the link 262 and by turning the segment 258 lowers the driver bar slide 212 toward the shoe and relative to the driver bar 216.

During this movement, the tack, which has previously been delivered to an inclined passage 282 in the lower end of the driver bar slide by means of the tack separating mechanism 42 and a flexible tack delivering tube 284, is permitted to drop into the tack nozzle 224 when the driver bar slide has been drawn down sufficiently for the inclined passage to come below the lower end of the tack driver 218. The tack nozzle 224, therefore, is thus lowered from a raised loading or tack-receiving position to a lowered tack-driving position in proximity to the shoe being operated upon. The degree of proximity is determined by the adjustment of the turn buckle 266 constituting a part of the link 262, and the lowermost position of the tack nozzle 224 may be varied up or down as desired by suitable adjustments thereof. Obviously, since the length of travel of the driver bar slide 212 is invariable for any given adjustment of the set screw 156, the height of the tack nozzle when in its raised tack-receiving or loading position is varied up or down in accordance with said adjustments. Therefore, in order to effect a reliable delivery of tacks into the inclined tackway passage 282 at the lower end of the driver bar slide, and to prevent the jamming of tacks therein, the flexible delivery tube 284 is provided with a vertically adjustable section 288 (Figs. 5 and 19) which is carried by an adjustable plate 290 provided with a tongue 292 having a sliding engagement with a suitable way in the lower portion of the side frame 34. The plate 290 is provided with an elongated slot 294, through which projects a bolt 296, for rigidly securing said plate and therefore the tube section 288 in any adjusted position. The upper end of the tube section 288 is enlarged and has a telescopic connection 298 with the lower end of the delivery tube 284, while the lower end thereof is tapered and adapted to fit within a funnel shaped opening leading to the inclined tackway 282. The inclination of the tube section 288 always corresponds to that of the tackway 282. By means of this construction it is obvious that regardless of the height of the tack nozzle 224 in its raised loading position, the

tube section 288 may be so adjusted in position as to register exactly with the inclined tackway passage 282. Therefore, the proper delivery of the tacks to the tackway passage 5 is ensured and the possibility of the tacks becoming jammed is obviated.

During the lowering movement of the tack nozzle, the driver bar slide 212 acts to continually place tension upon the driver 10 spring 234, since the driver bar 216 is held from downward movement by reason of its head 226 being above the roll 244 on the latch lever 242. Just as the tack nozzle reaches the shoe, as shown in Fig. 7, the cam 15 254 on the driver bar slide engages the boss 252 on the latch lever 242 and pushes said lever to the right, as viewed in Fig. 4, so as to withdraw the roll 244 from beneath the head 226 of the driver bar 216. This immediately releases the driver bar to the action 20 of the now fully tensioned driving spring 234 and the tack contained in the tack nozzle 224 is driven into the shoe by the tack driver 218, the parts at this time being as 25 shown in Fig. 7.

The driving crank 118 has now passed through a half revolution and the return forward movement of the welt-butting cutter slide 142 is thereafter effected, first relatively 30 to the carrier 152 which causes the links 148 and 150 to tilt backwardly until the rear end of the carrier engages the shoulder 154, as shown in Fig. 8. This backward tilting movement of the carrier raises the forward end thereof and therefore elevates the welt-butting cutter 154 from the shoe.

The continued forward motion of the carrier slide 142 returns the carrier and the cutter to their initial positions, as shown in Fig. 4, and during this movement the carrier actuates the link 262 to reversely rotate the segment 258 and raise the driver bar slide 212 from its lowered position, indicated in Fig. 8, to its initial raised position, as shown 45 in Fig. 4. Since the head 226 of the driver bar 216 rests at this time upon the upper end of the driver bar slide, the driver bar and one end of the driving spring 234 are both raised together until the latch lever 242 is tilted outwardly by the engagement of the cam 250 with the roll 244, and the head 226 eventually rests upon said roll and is held in its raised position with the driving spring 50 untensioned.

During the rearward movement of the cutter slide 142, the friction plug 270 offers sufficient resistance to prevent movement of the segment 258 and associated tacker mechanism during the first part of the operation 55 of the crank 118 to lower the cutter 154, and provides means for ensuring that the cutter carrier 152 is moved toward and from the welt support or crease finder about its pivotal connection with the cutter slide 142. The plug 270 performs a like function to re-

strain the carrier from moving relative to the slide at the start of the return forward movement, thus raising the cutter from the shoe before the carrier is advanced by the slide to its initial forward position, where 70 it is in readiness for another cycle of operations.

From the foregoing description it is clear that both the welt-butting and tacker mechanisms are operated by a single actuator and 75 in sequence to first butt the respective ends of the welt and thereafter drive the tacks.

As has already been stated, the pressure of the crease finders 52 against the shoe during the welt-butting operation is relatively light, being only such as is necessary to support the shoe in position while the ends of the welts are butted. According to the present invention, power-actuated means is provided for automatically increasing the inward pressure of the crease finders subsequent to the welt-butting operation for the purpose of lasting in the upper and associated parts and bringing them 85 into their final positions preparatory to the 90 tack driving operation.

Referring particularly to Figs. 1, 9 and 10, this end is accomplished by means of a member 300 which is secured to the forward end of a rod 302 that is carried beneath the H-shaped connecting rod 124. This rod 302 is slidably mounted thereon in an apertured depending lug 304 and a downwardly projecting cylindrical bearing member 306. The inner end of the rod 302 is screw-threaded 100 into a sleeve 308 that is slidably positioned in a cylindrical opening in the bearing member 306, and disposed between the lug 304 and the forward end of the sleeve 308 is a coiled spring 310, the strength of 105 which may be adjusted as desired by screwing the rod 302 into the sleeve 308.

Subsequent to the welt-butting operation and while the cutter is traveling over the guard plate 198, the rearward movement of the piston 120 brings the member 300 into cooperative engagement with the head 80 of the arm 78 in the sockets of which are located the inner ends of the struts 82, constituting the operating toggle 110 for the swinging side frames. As the rearward movement of the piston 120 and the member 300 is continued, the arm 78 is forced to the left, as viewed in Fig. 9, under a yielding pressure determined by the 115 adjustment of the spring 310. Thus, the pressure tending to straighten out the toggle formed by the struts 82 is augmented and the swiveling side frames 32 and 34, together with the crease finders 52 carried thereby, are accordingly forced inwardly to cause the crease finders to subject the upper 120 of the shoe to an increased predetermined pressure and effect the lasting in thereof into final position. The lasting operation 125

is so timed that the upper is properly positioned to be secured to the insole prior to the operation of the tacking mechanism. This automatic lasting operation is of special importance since uniform results are secured, by reason of being accomplished entirely independently of the operative, while it also has the material advantage of relieving the operative of the care and effort previously required for manually performing this function.

During the welt-butting operation the cutters 154 are apt to become gummed up with waxed threads and excess wax, while the severed waste ends of the welt frequently become jammed in between the cutters and the presser feet 162 in such manner that considerable difficulty is experienced in dislodging them. Provision is, therefore, made for scraping off the cutters and removing the waste ends subsequent to each welt-butting operation.

This means is best shown in Figs. 2, 3, 4, 16 and 17, and having reference to these figures, the scraping and waste-removing mechanism associated with the left-hand side frame will now be described. This mechanism comprises a substantially triangular scraper, or removing implement 312, which is located directly above the cutter 154 in sliding engagement with the upper surface thereof. The implement 312 is fixed to the inner end of a rod 314 that is laterally slidable through an aperture in the forward end of the cutter carrier 152 and projects outwardly therefrom. The outer end of the rod 314 is provided with a slide block 316 which is fixedly keyed thereto and which is adapted to slide within a way 318 provided in a bracket 320 that is bolted to the outside of the cutter carrier. This bracket 320 is provided with a laterally and forwardly extending flange or projection 322, the outer end of which constitutes a bearing for an operating lever 324, having a pair of spaced arms 326 which straddle the bearing member 322 and which are pivotally mounted thereon by means of a pivot pin 328. The operating lever 324 is provided with a rearwardly projecting arm 330 having a boss 332, which extends into, and cooperates with, the sides of a groove or recess 334 that is provided in the upper face of the slide block 316. The operating lever 324 also embodies a head 336 in a recess of which a spring-pressed pin or detent 338 is disposed. The end of this pin is adapted to project into a suitable recess in the bearing member 322 to locate the pivotally mounted operating lever 324 in proper position during a portion of the cycle of operations, as will be hereinafter more fully set forth. The operating lever 324 is furthermore provided with an extension or tail piece 340

that is adapted for cooperative engagement with one end of a yielding stop or bumper 342, that is pivotally mounted upon a vertical pin 344 that projects downwardly from the upper wall 346 of a laterally extending box-like casing 348, constituting an integral part of the face plate 276 that is bolted to the outside of the side frame 32. The other end of the bumper 342 is provided with a socket which receives a coiled spring 349 which serves the purpose of absorbing the shock occasioned by the engagement of the tail piece 340 with the opposite end of the bumper 342, as will hereinafter appear.

With the exception of the spring-cushioned bumper 342, the other parts of the removing and scraping mechanism already described are mounted upon, and are movable with, the cutter carrier 152 and therefore participate in the back and forth and up and down movements of said carrier and its welt-butting cutter.

After the welt-butting cutter has been dropped from its initial raised position (Fig. 4) to its lowered operative position, as shown in Fig. 6, and during the rearward cutting stroke thereof, the scraping and removing mechanism remains idle in the position shown in Fig. 2, except for a bodily movement of translation. During this movement the mechanism is maintained in position by the spring-pressed detent 338. Subsequent to the welt-butting and tacking operation, however, this mechanism is raised in position when the cutter carrier and cutter are elevated from the work, preparatory to their forward return movement to their initial position. At this time a cam roll 350 that is carried by the operating lever 324 occupies the position indicated in dot-and-dash lines in Fig. 2, and having been raised in position, is brought into cooperative relation with a cam member 352 that is bolted to the underside of the upper wall 346 of the outwardly projecting casing 348.

During the return movement of the cutter, the roll 350 traverses the cam 352 and is progressively forced inwardly to a position illustrated in Fig. 3. The operating lever 324 is thus rotated about its pivot and, through the agency of the slide block 316 and the rod 314, the scraping and removing implement 312 is actuated in a lateral inward direction. Thus, the scraper is caused to slide over the upper surface of the cutter 154 whereby any waxed threads and wax are scraped therefrom and the severed waste ends of the welt are removed from between the cutter and presser foot. A spring 354, which surrounds the rod 314, serves to cushion the inward movement of the scraper.

As the forward return movement of the

cutter carrier and cutter continues, the tail-piece 340 is brought into engagement with the spring-cushioned bumper 342, which serves to actuate the operating lever 324, 5 the slide block 316, the rod 314 and the implement 312 in the opposite direction into their initial positions as shown in Fig. 2, where they are restrained by the spring-pressed detent 338. As already stated, the 10 shock of this engagement is taken up by the spring 349. The position of the bumper 342 is determined by an adjustable set screw 356 in the forward end of the casing 348.

The cutter carrier and cutter having been 15 returned to their forward raised positions, as shown in Fig. 4, the scraping and removing mechanism just described is also elevated in position, the roll 350 being in the plane of the cam 352, in which position the 20 cycle of operations of the machine is arrested.

From the foregoing description it will be understood that the respective cutters 154 are scraped and cleaned simultaneously and 25 that the severed ends of the welt are removed and ejected inwardly by means of the scraping and waste-removing implements 312. Moreover, the actuating mechanisms for the waste-removing implements 30 are located on the outer sides of the cutter carriers where ample room is available for their mounting and whereby the restricted space between the respective swinging side frames is left as free as possible from obstructions. 35

Although the invention has been set forth as embodying more or less specific structural details and arrangement and location of parts, those skilled in the art will understand that many modifications may be made therein without departing from the spirit and scope of the invention.

Having illustrated and described the preferred embodiment of the invention that 40 which is claimed as new is:

1. A welt-butting machine having, in combination, means for supporting a welted unsoled shoe, a cutter for butting the end of the welt, a cutter carrier, means for actuating the carrier and cutter longitudinally of the shoe, and means disposed in sliding engagement with the upper surface of the cutter and supported by and movable with the cutter carrier for removing material adhering thereto. 55

2. A welt-butting machine having, in combination, means for supporting a welted unsoled shoe, a cutter for butting the end of the welt, a cutter carrier, means for actuating the carrier and cutter longitudinally of the shoe, and means disposed directly above the cutter and movable therewith for engaging and laterally removing the severed waste ends of the welt. 60

3. A welt-butting machine having, in combination, means for supporting a welted unsoled shoe, a cutter for butting the end of the welt, a cutter carrier, means for actuating the carrier and cutter, and laterally movable means disposed directly above and in sliding engagement with the cutter for scraping off the cutter and laterally removing the severed waste ends of the welt. 65

4. A welt-butting machine having, in combination, means for supporting a welted unsoled shoe, a movable cutter for butting the end of the welt, and means disposed in sliding engagement with the cutter for scraping off the cutter after each cutting operation. 75

5. A welt-butting machine having, in combination, means for supporting a welted unsoled shoe, a cutter for butting the end of the welt, a cutter carrier, means for actuating the carrier and cutter longitudinally of the shoe, and laterally movable means supported on the inside of said cutter carrier and means supported on the outside of said carrier for laterally actuating said movable means towards the shoe to remove the severed waste ends of the welt. 80

6. A welt-butting machine having, in combination, a pair of swinging side frames, crease finders projecting inwardly therefrom to engage the crease of a welted unsoled shoe and support the shoe in position to be operated upon, cutter carriers slidably mounted on said side frames, inwardly projecting cutters secured to said carriers, laterally movable waste-removing implements mounted on the inside of said cutter carriers, stationary cams supported by said side frames on the outside of said cutter carriers, and mechanism mounted on the outside of said carriers and in cooperative relation with said cams for actuating the waste-removing implements toward the shoe to cause them to laterally remove the severed waste ends of the welt. 95

7. A welt-butting machine having, in combination, means for positioning a welted unsoled shoe and supporting an end of the welt, and means for butting the end of the welt, said two means being constructed and arranged to produce on the welt a bevel inclined both longitudinally and transversely thereof and to squarely cut off the end of the welt. 105

8. A welt-butting machine having, in combination, means for supporting an end of the welt of a welted unsoled shoe, and a cutter movable longitudinally of the shoe for scarfing off the end of the welt on a bevel extending both longitudinally and transversely outward of the welt, the scarfed bevel being so located as to leave the stitches intact. 120

9. A welt-butting machine having, in combination, means for supporting a welted un- 125

soled shoe, and means for scarfing off an end of the welt on a bevel extending both longitudinally and transversely outward of the welt and for squarely cutting off the end of the welt, said bevel being so located as to leave the stitches intact.

10. A welt-butting machine having, in combination, a crease finder for engaging the crease of a welted unsoled shoe at the rear end of the welt and supporting the end thereof during the butting operation, said crease finder being inclined upwardly toward the end of the welt and transversely upwardly away from its inner edge, a shear plate disposed at the upper end of the crease finder toward the end of the welt, and a welt-butting cutter operating in the longitudinal direction of the welt for beveling the end of the welt so supported by the crease finder both longitudinally and transversely outward, and for cooperating with said shear plate to squarely cut off the welt end.

11. A welt-butting machine having, in combination, a welt-butting cutter, means for supporting a welted unsoled shoe comprising a crease finder for engaging the crease at the rear end of the welt and supporting the end thereof during the butting operation, the upper surface of said crease finder being so inclined and shaped as to support the welt end with respect to the cutter in such manner as to cause said cutter to bevel off the welt both longitudinally and transversely outward, without cutting the stitches, and to squarely cut off the welt end.

12. A welt-butting machine having, in combination, means for supporting a welted unsoled shoe comprising a crease finder for engaging the crease at the rear end of the welt and supporting the end thereof during the butting operation, the upper surface of said crease finder being inclined upwardly toward the end of the welt and upwardly away from a curved inner edge having its maximum curvature at the welt end thereof, a presser foot for engaging the upper surface of the supported welt end and holding it down in engagement with the upper surface of the crease finder, and a welt-butting cutter movable in the longitudinal direction of the welt for beveling off the supported welt end both longitudinally and transversely without cutting the stitches, and for squarely cutting off the welt end.

13. A welt-butting machine having, in combination, means for supporting a welted unsoled shoe comprising a crease finder for engaging the crease at the rear end of the welt and supporting the end thereof during the butting operation, the upper surface of said crease finder being inclined upwardly toward the end of the welt, and upwardly away from the inner edge thereof, a presser foot for engaging the upper surface of the

supported welt end and holding it down in engagement with the inclined upper surface of the crease finder, and a welt-butting cutter arranged for movement in a horizontal plane for beveling off the supported welt end.

14. A machine for operating upon welted unsoled shoes having, in combination, means for supporting a shoe, means for butting the respective ends of the welt thereof, automatic means for lasting in the shank portion of the upper subsequently to the butting operation, and means for thereafter tacking the lasted upper to the insole.

15. A machine for operating upon welted unsoled shoes having, in combination, means for supporting a shoe, means for butting the respective ends of the welt thereof, and automatic means for lasting in the shank portion of the upper subsequently to the butting operation.

16. A machine for operating upon welted unsoled shoes having, in combination, means for supporting a shoe, means for butting the respective ends of the welt thereof, power operated means rendered effective after the welt-butting operation for lasting in the shank portion of the upper, and means for determining the pressure exerted thereby.

17. A machine for operating upon welted unsoled shoes having, in combination, supporting means, crease finders carried thereby, cutters for butting the respective ends of the welt, mechanism including a treadle for actuating said supporting means to cause said crease finders to engage and support the shoe in position to be operated upon, and means independent of said treadle for actuating said supporting means and crease finders to last in the upper.

18. A machine for operating upon welted unsoled shoes having, in combination, supporting means, crease finders carried thereby, cutters for butting the respective ends of the welt, treadle mechanism for actuating said supporting means to cause said crease finders to engage and support the shoe in position to be operated upon, and power operated means automatically operative subsequent to the welt-butting operation for actuating said supporting means and crease finders to last in the upper under predetermined pressure.

19. A machine for operating upon welted unsoled shoes having, in combination, supporting means, crease finders carried thereby, cutters for butting the respective ends of the welt, mechanism for actuating said cutters, treadle mechanism for actuating said supporting means to cause said crease finders to engage and support the shoe in position to be operated upon, and means actuated by said cutter actuating mechanism for causing

- said crease finders to last in the upper under a predetermined pressure subsequent to the butting operation.
20. A machine for operating upon welted unsoled shoes having, in combination, supporting means, crease finders carried thereby, cutters for butting the respective ends of the welt, mechanism for actuating said cutters, mechanism including a treadle for causing said supporting means to force the crease finders under limited pressure into supporting engagement with the shoe, and automatic means operated by said cutter actuating mechanism and independent of said treadle for increasing the pressure of said crease finders to a limited degree to cause them to last in the upper. 65
21. A welt-butting machine having, in combination, means for supporting a welted unsoled shoe in position to be operated upon, a movable cutter carrier provided with a transverse V-shaped groove, an elongated V-shaped cutter corresponding in angularity throughout its entire length to that of the sides of the V-shaped groove, said cutter being seated in said groove and having one end thereof projecting laterally from the carrier into position to butt the end of the welt of the shoe, and a clamping member secured to said carrier for engaging the back of the cutter and firmly holding it in position in said groove. 70
22. In a machine for removing surplus material from shoes, a knife, means for operating the knife to remove material from the shoe, and means movable relatively to the knife in the direction of the knife edge to remove the severed material from the knife. 75
23. In a machine of the class described, a support for shoe material, a knife, means for relatively moving the knife and support to cause the knife to sever a portion of the material, and a clearer movable relatively to the knife in the direction of the knife edge to remove the severed material from the knife. 80
24. In a welt butting machine, means for supporting the opposite welt ends, knives movable longitudinally of the welt relatively to the supports to sever the welt ends, and means carried by the knives and operated during the return movement of the knives to remove the severed material from the knives. 85
25. In a welt butting machine, means for supporting the opposite welt ends, knives movable relatively to the supports to sever the welt ends, and means carried with the knives and operated during the return movement of the knives to force the severed material inwardly of the shoe. 90
26. In a machine of the class described, welt butting mechanism including a welt support and a cutter relatively movable longitudinally of the welt to scarf off the welt ends, power operated means for actuating the welt butting mechanism, and a clearer acting automatically to remove the welt end from the knife. 95
27. In a welt butting machine, a knife having an edge extending transversely of the welt, a carrier for the knife, a clearer arranged on the knife carrier for movement parallel to the knife edge in close proximity thereto to clean off any material that may adhere to the knife, means for operating the knife to cut the welt and to return to initial position, and means for operating the clearer during said return of the knife to initial position. 100
28. The combination of a welt butting knife mounted for movement in one plane to butt the welt and to return to initial position in a higher plane, means for removing the cut-off welt end from the knife, and means acting as an incident to said last-mentioned movement of the cutter for actuating the welt end removing means. 105
29. In a welt butting machine, the combination of a welt butting knife movable longitudinally of the welt to scarf off the welt end, a clearer arranged to move with the cutter and movable relatively thereto parallel to the cutting edge of the cutter to remove the welt end from the cutter, and means for effecting said relative movement after the welt end has been scarfed off. 110
30. In a welt butting machine, a welt butting knife movable longitudinally of the welt to scarf off the welt end, a clearer arranged to move with the cutter and movable relatively thereto parallel to the cutting edge of the cutter to scrape the surplus severed material from the cutter, and a relatively stationary cam acting during an idle movement of the cutter to operate the clearer. 115
31. In a welt butting machine, means for supporting the opposite welt ends, knives movable longitudinally of the welt relatively to the supports to sever the welt ends, clearers movable with the knives and movable transversely of the direction of cutting movement of the knives, and means operating after the cutting action of the knives to move the clearers in said transverse direction. 120
32. In a shoe machine, means for performing a plurality of operations upon the shoe bottom, upper tightening means, and means for increasing the action of the upper tightening means between the operations of said operating means. 125
33. In a shoe machine, the combination of cutters and tackers arranged to operate successively on the shoe, blades acting to tighten the upper of the shoe over the shoe bottom, and a member operated in time relation to the cutters and tackers to increase

- the tightening action of the blades between the operations of the cutters and tackers.
34. In a shoe machine, means for performing a cutting operation, means for performing a securing operation, means for tightening the upper, and automatic means for varying the action of said tightening means after the cutting operation.
35. In a machine of the class described, 10 welt butting means, upper securing means, means engaging the welt crease to tighten the upper and support the welt during the butting operation, manual means for effecting operation of the tightening means before the machine is started, and power means for increasing the tightening effect of the tightening means after the machine starts.
36. In a shoe machine, the combination of 20 blades movable in a plane parallel to the shoe bottom for engaging the welt crease of a welted shoe on opposite sides of the shoe, a spring, power means operating through the spring to cause the blades to tighten the upper over the shoe bottom, and power operated knives acting lengthwise of the shoe at a slight angle to said blades to skive off the welt ends.
37. In a machine of the class described, the combination of welt butting means, upper 30 tacking means, manually operated means acting in the welt crease to tighten the upper over the last bottom and to support the welt during the operation of the butting means, and power operated means for effecting an additional tightening of the upper prior to the action of the upper tacking means.
38. In a machine of the class described, the combination of welt butting means, upper tacking means, welt crease engaging 40 means, a plurality of springs, means acting through one of the springs to tighten the upper before the operation of the butting means, and means acting through another spring for tightening the upper before the operation of the tacking means.
39. In a machine of the class described, the combination of welt butting cutters, upper tackers, welt supports acting in the welt crease to tighten the upper over the shoe bottom, and a power actuated member including a spring for effecting tightening 50 action of the welt supports.
40. In a welt butting machine, welt supports to support the opposite welt ends, butting cutters movable longitudinally of the welt to scarf off the welt ends, power means acting to force the welt supports toward each other to tighten the upper, and means for securing the upper so tightened to the shoe.
41. In a welt butting machine, welt supports to support the opposite welt ends of a welted, unsoled shoe, butting cutter movable longitudinally of the welt to scarf off the welt ends, power means acting to force the 60 welt supports toward each other to tighten the upper, and means for securing the upper so tightened to the shoe.
42. In a welt butting machine, welt supports to support the welt ends of a welted, unsoled shoe, butting cutters movable longitudinally of the welt to scarf off the welt ends, means acting after the welt is butted to tighten the upper over the shoe bottom, and tackers movable into operative relation to the tightened upper to secure the upper 70 to the shoe bottom.
43. In a welt butting machine, welt butting means, tacking means, welt supports, manual means for moving the welt supports into welt supporting position prior to the 80 butting operation and effective upon final movement to start the machine, means for maintaining the welt supports in position independently of said manual means, automatic means for operating the welt supports 85 to tighten the upper after the welt butting operation and prior to the tacking operation, and means for operating the tackers to secure the tightened upper.
44. A welt butting machine having, in 90 combination, means for supporting a welt end of a welted, unsoled shoe, means for scarfing off the end of the welt, and means for holding the welt end on the support, the welt engaging surfaces of the support and 95 holding means being so formed relatively to the path of the scarfing means that the welt is cut on a bevel extending both longitudinally and transversely outwardly of the welt, the scarfed bevel being so located as 100 to leave the inseam stitches intact.
45. In a welt butting machine, a co-operating welt support and cutter relatively movable to bevel the welt end longitudinally and relatively arranged to cause the 105 welt to be cut squarely across the end and to cause the bevel to be widest at the square end and to taper to a point at the outer edge of the welt where the bevel begins.
46. In a welt butting machine, a welt support, a cutter co-operating therewith, and means for relatively actuating the support and cutter to scarf off the end portion of the welt, the cutter and welt supporting surface of the welt support being relatively arranged to cause the surface of the cut made by the cutter to be right-triangular in shape. 115
47. In a welt butting machine, a welt support, a cutter co-operating therewith, and means for relatively actuating the support and cutter to scarf off the end portion of the welt, the welt support and cutter being relatively so formed that the end of the welt will be cut at right angles to the outer edge of the welt and the line between the scarfing cut and the uncut surface of the welt will extend from a point adjacent to the inseam upon the square end of the welt to a point on the outer edge of the welt. 120
48. In a welt butting machine, a welt sup- 125
- 130

port, a cutter co-operating therewith, and means for relatively actuating the support and cutter to scarf off the end portion of the welt, the support and cutter being relatively 5 formed and arranged to form a line between the scarfing cut and the uncut surface of the welt extending inwardly obliquely toward the end of the welt and to cut the end of the welt at right angles to the outer edge of the 10 welt.

49. In a welt butting machine, the combination of welt butting cutters movable longitudinally of the shoe to butt the welt, welt supports engaging in the welt crease to 15 support the welt, and shoulders at the rear extremities of the supports arranged to extend inwardly beyond the welt and to serve as indices with respect to which the shoe may be positioned longitudinally to show the operator 20 how much of the welt ends will be removed, the cutters co-operating with said shoulders to sever the welt ends even with the upper surfaces of the shoulders.

50. In a welt butting machine, the combination of welt butting cutters movable longitudinally of the shoe to butt the welt, welt supports engaging in the welt crease to support the welt, shoulders at the rear extremities of the supports which are highest 30 at their inner ends, means operating in advance of the welt butting cutters for forcing the welt down behind said shoulders, and means for operating the welt butting cutters in the plane of the top of the shoulders to 35 sever the welt ends.

51. In a welt butting machine, the combination of welt butting cutters movable longitudinally of the shoe to butt the welt, welt supports engaging in the welt crease to support the welt, and shoulders at the rear extremities of the supports over which the cutting edges of the knives pass and with which they co-operate to sever the ends 40 of the welt.

45 52. In a machine of the class described, the combination of a knife having a uniform cross-section, a holder for the knife having a groove to receive a portion of the cutting edge of the knife without contact of the edge with the holder, and a clamp secured to the holder and bearing on the back of the knife to force it into the groove.

53. In a machine of the class described, the combination of a knife having a prismatic cross-section, a holder having faces to engage the faces of the knife which form its cutting angle, a clamp engaging another face of the knife, and means for forcing the clamp against the knife to hold said faces 55 of the knife against said faces of the holder.

54. In a machine of the class described, the combination of a knife having a prismatic cross-section, a holder having a V-shaped notch to receive the cutting angle of the knife and support the faces which form

its cutting edge, said holder having a recess at the apex of the V-shaped notch to prevent contact of the cutting edge with the holder, and a clamp to hold the knife in the notch.

55. In a machine of the class described, 70 means for locating a shoe, a pair of knives of uniform triangular cross-section, knife holders at opposite sides of the shoe having notches with walls inclined to correspond to the angle between the surfaces forming the 75 cutting edges of the knives and adapted to receive the outer end portions of the knives with their inner ends projecting toward the shoe at opposite sides thereof, and means for holding the knives in the notches, the 80 knives being interchangeable when their cutting portions are dulled to bring into action the portions of the knives which were in the holders.

56. In a machine of the class described, 85 the combination of a pair of knives each of uniform cross-section, and holders each arranged to enclose one end portion of one of the knives, the knives being presented by the holders with their acting portions projecting toward each other beyond the holders from opposite directions, the knives being 90 interchangeable in their holders to bring into action the portions of the knives previously in the holders.

57. In a welt butting machine, welt supporting means, welt butting means, tacking means, connected mechanism for operating first the butting means and then the tacking means, and an adjustable link in the said 100 connected mechanism, said link comprising members respectively internally and externally threaded.

58. In a machine of the class described, 105 welt butting means and tacking means movable together over the shoe bottom, shoe locating means, upper tightening means, a single actuator operated by power to move the butting means to butt the welt, to press the tightening means into the welt crease, and to lower the tacking means into operative relation to the shoe to secure the upper, and means for varying the lower position of the tacking means without altering the 110 movement of the actuator.

59. In a machine of the class described, 115 welt butting means, an actuator for the butting means, a tacker movable into position to insert a tack in the shoe, and connections including a link between the actuator and the tacker to move the tacker, said link comprising telescoping members having threaded relation to each other and having yokes at their outer ends.

60. In a welt butting machine, tacking 120 means arranged to secure the upper at each side of the shoe, welt supports acting in the welt crease to tighten the upper over the last adjacent to the points where it is to be secured, a spring, power-operated means act- 125

ing upon the welt support by compression of said spring to tighten the upper, and means for operating the tacking means to secure the tightened upper to the innersole.

5 61. In a machine for operating on shoes, the combination of means for tightening an upper over the last bottom at opposite sides

of the last, power means including yielding connections for operating said means to tighten the upper, and automatic means for 10 securing the tightened upper to the shoe bottom.

EDWARD ERICKSON.
